UNITED STATES PATENT OFFICE.

EDWARD W. HERENDEEN, OF GENEVA, NEW YORK.

SPRING-TOOTH HARROW.

SPECIFICATION forming part of Letters Patent No. 359,970, dated March 22, 1887.

Application filed October 11, 1886. Serial No. 215,920. (No model.)

To all whom it may concern:

Be it known that I, EDWARD W. HERENDEEN, of Geneva, in the county of Ontario and State of New York, have invented certain 5 Improvements in Spring-Tooth Harrows, of which the following is a specification.

My invention has reference to that class of harrows in which elastic or spring teeth attached at their upper ends to a frame have 10 their lower ends or points curved downward and forward to enter the soil. Teeth of this general character have been known in the art for many years, and have been attached to frames of various forms by a variety of fastening devices adapted to permit their adjustment.

The aims of my invention are principally to provide an improved frame and improved means for attaching the spring-teeth. 20 To this end it consists, essentially, in constructing the frame of metallic channel-bars—that is to say, bars having vertical flanges at their edges; in providing these flanges with openings through which the end of the tooth 25 passes, and in combining therewith fastening devices, as hereinafter described.

In the accompanying drawings, Figure 1 represents a perspective view of a tooth attached to a frame bar or beam in accordance 30 with my invention, the bar in this instance having depending flanges. Fig. 2 is a similar view illustrating the tooth attached to a bar with upturned flanges. Fig. 3 is a perspective view showing a section of the frame bar 35 or beam, with the openings for the tooth therethrough and with the tooth-clamping plate in position. Fig. 4 is a perspective view of the clamping or confining plate in one of its forms. Fig. 5 is a vertical cross-section through one 40 of the beams or frame-bars, with the tooth secured thereto by means of a central bolt.

In carrying my invention into effect I first provide metallic channel bars or beams A, in any suitable size and number, and bolt or otherwise connect them together to produce a frame of the required form. These channel-bars are preferably rolled from mild steel with a temper or hardness sufficient to give them a suitable hardness and elasticity. Through the 45 flanges of each bar, at suitable points in its length, I form transverse openings a' of a

form and in a position adapted to receive the end of the tooth B. This tooth I prefer to form in the ordinary manner represented in the drawings of a flat form in cross-section, 55 with its upper end curved downward and rearward, whereby it is adapted to be extended through the beam from side to side and through the openings a' a', as represented in Figs. 1, 2, and 3.

In harrows as ordinarily constructed the beams extend in a direction oblique to the line of travel, while the tooth is curved longitudinally in a vertical plane lying in the direction of travel. In consequence of this fact, the end 65 of the tooth passes obliquely through the beam. This oblique position of the tooth, in connection with the curvature of the latter, renders it necessary to incline the slots a' a' in opposite directions from the horizontal, as shown in the 70 several figures, this formation adapting them to receive and closely embrace the tooth, which is consequently held rigidly in position by the beam. The parts are so fitted that the end of the tooth may be adjusted longitudinally 75 through the beam, in order to vary the position of the point, to compensate for wear or for other purpose.

In order to prevent the accidental movement of the tooth through the beam, I propose 80 to secure the same in position therein by fastening devices of any appropriate character. I may provide the tooth with a series of holes, b, at different points in its length and secure it in position by a vertical bolt, c, passing 85 through the tooth and the beam, as represented in Fig. 5. This construction, while securing the tooth firmly in position, admits of its being adjusted longitudinally at will. I prefer to employ, however, in place of the bolt passing 90 through the tooth, a plate bearing upon the tooth, as shown at D, and secured by bolts C. This plate, which is fitted in the hollow side or channel of the beam, may be of any appropriate form. In Figs. 2 and 3 the plate extends 95 entirely across the inside of the beam, bearing against the inner walls of its flanges and serving to prevent them from being accidentally bent inward. It bears upon the tooth at a single line only midway between the two 100 flanges. Being thus applied, the plate forces the tooth firmly against the walls of the slots,

the elasticity of the tooth being brought into play and serving to maintain a close contact with the supporting-surfaces.

In Fig. 4 I have illustrated a cruciform plate, the four arms of which bear against the inner faces of the flanges to assist in holding them in proper position. When this plate is used, I prefer to form the same with the raised rib to bear upon the tooth midway between the flanges.

It will be observed that in my structure the tooth has two bearing or supporting surfaces on one side and a single bearing-surface on the other, the latter being midway between the former.

In constructing the harrow the channel-bars may be used, as in Fig. 1, with their flanges extending downward, or they may be employed, as in Fig. 2, with their flanges extending upward. Inasmuch as the bars ride during a great part of the time upon the surface of the ground and assist in effecting the reduction or pulverization of the soil, I prefer the construction represented in Fig. 1, the edges of the flanges in such case serving as an efficient aid in the reduction of the soil. It is in this connection that the use of the plates to support the flanges internally is of special advantage. In order to give increased strength and durability to the forward flange, which will receive the greater part of the wear when the bars are used as in Fig. 1, I may form the forward flange of greater thickness than the other, as represented in Fig. 5; but it is to be understood that this is not a necessary feature of the bar.

In the event of the forward flange becoming unduly worn, bars constructed on my plan may be reversed or turned end for end, the teeth be-

ing of course changed from side to side, and thus the unworn flange brought into position at the front.

The essence of my invention resides in the employment of channel-bars the flanges of which are provided with slots or openings adapted to receive the ends of the spring-teeth and give support thereto, and it is manifest that the form and position of these openings may be modified as circumstances may require or fancy dictate without passing beyond the limits of my invention.

Having thus described my invention, what I claim is—

1. In a spring-tooth harrow, the combination of the elastic tooth, the metallic channel-bar provided in its flanges with openings through which the end of the tooth is passed, and a fastening device, substantially as described, applied within the bar to secure the tooth in place.

2. A channel-bar and an elastic harrow-tooth seated in its two flanges, in combination with a fastening device, as described, acting upon the tooth midway between the flanges only, whereby the tooth is held to its bearings with an elastic or yielding pressure.

3. In a harrow, the metallic channel-bar provided in its respective flanges with slots inclined in opposite directions, as described, whereby it is adapted to receive and hold a curved obliquely-placed tooth.

In testimony whereof I hereunto set my hand in the presence of two attesting witnesses.

EDWARD W. HERENDEEN.
